UNITED STATES PATENT OFFICE.

EDWARD A. DEWALD, OF MASSILLON, OHIO.

JAR CLOSURE.

Application filed May 22, 1924. Serial No. 715,078.

To all whom it may concern:

Be it known that I, EDWARD A. DEWALD, a citizen of the United States, residing at Massillon, in the county of Stark and State 5 of Ohio, have invented certain new and useful Improvements in Jar Closures, of which the following is a specification.

This invention relates to jars of the type used for canning purposes, and more especially to a novel construction of closure 10 for the jar.

The object of the present improvement is to provide a jar closure which forms an air tight seal between the lid and the mouth of 15 the jar, the usual standard rubber packing ring being compressed between the mouth of the jar and the lid; the central portion of the lid extending into the mouth of the jar, thus permitting the jar to be completely 20 filled with liquid, eliminating the possibility of an air pocket; the lid being arranged to be easily and readily placed upon or removed from the jar, and to be tightly 25 retained in place when applied to the jar.

The above and other objects are attained 30 by providing a pair of diametrically opposed flanges around the neck of the jar, each flange having its under side inclined from one end toward the other and terminating at the larger end in a depending projection; a flanged lid being arranged to extend into the mouth of the jar, a standard 35 rubber packing ring being compressed between the flange of the lid and the rim of the mouth, the lid having a ball race in its top face near the periphery to receive a pair of glass balls carried in a metal yoke, provided with inclined feet for contact with the inclined under sides of the flanges upon the 40 jar neck.

An embodiment of the invention thus described in general terms, is illustrated in the accompanying drawing, in which—

Figure 1 is a vertical, sectional view of a 45 jar provided with the improved closure;

Fig. 2, a side elevation of the upper portion of the jar;

Fig. 3, a similar view substantially at 50 right angles to Fig. 2;

Fig. 4, a plan view of the jar;

Fig. 5, a plan view of the lid;

Fig. 6, a bottom plan view of the yoke; 55 and

Fig. 7, a transverse, sectional view of the yoke.

Similar numerals refer to similar parts throughout the drawing.

The improved jar is illustrated at 1 and provided with the reduced neck 2 around which are located the diametrically opposed, 60 peripheral flanges 3, the neck terminating in an annular rim 4 surrounding the mouth 5.

The under side of each flange 3 is inclined downward from one end to the other as 65 shown at 6, the smaller end of the flange being preferably tapered as at 7, the larger end terminating in the depending projection 8.

The present jar closure includes the lid 70 9, which is preferably molded glass having the annular flange portion 10 arranged to seat upon the rim 4 of the mouth. The central portion 11 of the lid is adapted to extend into the mouth of the jar to prevent an 75 air space between the contents of the jar and the lid; and for sealing the jar, the usual standard packing ring 12 is preferably placed upon the rim of the jar, forming a seal between the lid flange and the rim 80 of the jar.

A concentric raceway 13 is formed in the top of the lid 9, near the periphery thereof, and for the purpose of reducing the weight 85 of the lid, the central portion of the upper face thereof may be cut away as shown at 14.

As illustrated in Fig. 1, the flange 10 of the lid projects beyond the rim of the jar mouth, permitting the entrance of a knife 90 or similar tool between the lid and the adjacent flange 3, the flange acting as a fulcrum for the knife in prying the lid from the jar.

For the purpose of clamping the lid on the 95 neck of the jar, a yoke 15, preferably stamped from a strip of open hearth, drawn steel, is provided. This yoke comprises the central channel portion 16, the lower edges of which are provided at opposite end portions with the inturned lugs 17 for retaining the glass balls 18; and the depending leg portions 19 which are preferably flared in width at their lower ends and provided with the inclined L-flanges 20, which are 100 preferably concaved, and adapted to engage and operate under the inclined, annular flanges 3 of the jar.

The concaved inner edges of the L-flanges 105 20, will assist in quickly centering the yoke 110

upon the jar neck, and will prevent sidewise displacement of the yoke.

For the purpose of strengthening the legs 19 of the yoke, a rib 21 is formed in each leg, 5 merging into the central portion of the yoke at the upper end and terminating in the lower curved end 22, extended beneath the inclined flange 20.

In placing the closure upon the jar, the 10 standard rubber ring 12 is first stretched over the central portion of the lid 9 and the lid is then placed over the mouth of the jar, as shown in Fig. 1, the rubber packing ring 12 being located between the annular 15 flange 10 of the cover and the rim 4 of the mouth of the jar. The yoke is then slipped vertically over the neck of the jar, the legs thereof being received in the cut-out portions 23 between the ends of the flanges 3, 20 the balls 18 being received in the raceway 13 of the lid.

The yoke is then rotated around the neck of the jar, being turned toward the right, the L-flanges 20 thereof engaging and operating under the inclined lower faces of 25 the annular flanges 3 of the jar. As the yoke is rotated, the balls 18 will travel around the raceway 13 of the lid, preventing rotary movement of the lid with relation to the jar and leaving the lid stationary.

As the L-flanges 20 are moved toward the lower or larger ends of the annular flanges 3 of the jar, the lid will be tightly clamped upon the mouth of the jar, compressing the 35 rubber packing ring between the flange 10 of the lid and the rim 4 of the jar, forming an air tight seal at the joint.

The depending projections 8 at the lower or larger ends of the annular flanges 3, act 40 as reverse stops to prevent the yoke from being turned beyond the disengaging position when the yoke is removed to open the jar.

In assembling the lids upon the jars for 45 shipping, considerable time and labor may be conserved by placing the rubbers inside of the jars and clamping the glass lid directly upon the rim of the jar mouth, the L-flanges 20 of the yoke engaging the under 50 sides of the depending projections 8 at the lower or larger ends of the jar flanges 3, thus tightly clamping the glass lid upon the jar, without the necessity of placing the rubber upon each jar lid.

From the above, it will be obvious that 55 a very simple and efficient jar closure is provided. The ball race being located near the periphery of the lid, causes all of the clamping power to be exerted almost directly above the rim of the jar mouth. This permits the glass lid 9 to be of very light weight, and the ball race itself forms a corrugated structure, which tends to strengthen and reinforce the glass lid.

60 By providing the glass lid with the cen-

tral portion arranged to project into the mouth of the jar, the lid is easily centered upon the mouth of the jar, and the formation of an air pocket in the mouth of the jar is prevented. The glass lid being exposed to view, permits inspection of the 70 contents of the jar through the top.

I claim:

1. In combination with a jar having a pair of inclined, annular flanges around its neck portion, a closure including a lid arranged to compress a packing ring upon the mouth of the jar, a U-shaped yoke having L-shaped legs for engagement with the inclined, annular flanges, and a ball carried by the yoke 80 and movable longitudinally thereof for engagement with the lid.

2. In combination with a jar having a pair of inclined, annular flanges around its neck portion, a closure including a lid arranged to compress a packing ring upon the mouth of the jar and having a raceway in its upper face, a U-shaped yoke having L-shaped legs for engagement with the inclined, annular flanges, and balls carried by 90 the yoke for engagement with the raceway.

3. In combination with a jar having a pair of inclined, annular flanges around its neck portion, a closure including a lid arranged to compress a packing ring upon the mouth of the jar, a U-shaped yoke having L-shaped legs provided with inclined flanges for engagement with the inclined, annular 95 flanges, and a ball carried by the yoke and movable longitudinally thereof for engagement with the lid.

4. In combination with a jar having a pair of inclined, annular flanges around its neck portion, a closure including a lid arranged to compress a packing ring upon the mouth of the jar and having a raceway in its upper face, a U-shaped yoke having L-shaped legs provided with inclined flanges for engagement with the inclined, 110 annular flanges of the jar, and balls carried by the yoke for engagement with the raceway.

5. In combination with a jar having a pair of inclined, annular flanges around its neck portion, a closure including a lid arranged to compress a packing ring upon the mouth of the jar and having a raceway in its upper face, a U-shaped yoke having L-shaped legs for engagement with the inclined, annular flanges of the jar, balls carried by the yoke for engagement with the raceway, and means for preventing sideways displacement of the yoke.

6. In combination with a jar having a pair of inclined, annular flanges around its neck portion, provided with depending projections, a closure including a lid arranged to engage the mouth of the jar and having a raceway in its upper face, a U-shaped yoke 120

having L-shaped legs for engagement with the depending projections upon the inclined annular flanges, for clamping the lid directly upon the mouth of the jar, and balls carried by the yoke for engagement with the raceway.

7. A jar having a pair of inclined, annular flanges around its neck portion, a depending projection at the lower end of each flange, and a closure including a lid arranged to compress a packing ring upon

the mouth of the jar, a U-shaped yoke having L-shaped legs for engagement with the inclined, annular flanges, and balls carried by the yoke for engagement with the lid, 15 the projections upon the inclined, annular flanges forming stops to limit the opening movement of the yoke.

In testimony that I claim the above, I have hereunto subscribed my name.

EDWARD A. DEWALD.
